UNITED STATES PATENT OFFICE.

WILLIAM A. YOUNG AND GEORGE R. MOORE, OF MEDFORD, OREGON.

INTAKE-MANIFOLD HEATER.

Application filed April 20, 1921, Serial No. 462,782. Renewed November 7, 1923.

To all whom it may concern:

Be it known that we, WILLIAM A. YOUNG and GEORGE R. MOORE, citizens of the United States, residing at Medford, in the county 5 of Jackson and State of Oregon, have invented certain new and useful Improvements in Intake-Manifold Heaters, of which the following is a specification.

This invention relates to an improved 10 manifold heater for internal combustion engines, being particularly adapted for use on engines of Chevrolet design, and has as one of its principal objects to provide a particularly simple and at the same time efficient 15 device of this character which will utilize the heat of the exhaust gases of an engine for heating the walls of the engine intake manifold.

The invention has as a further object to 20 provide a device which may be readily applied and which will require no structural change in the intake manifold.

And the invention has as a still further 25 object to provide a device which may be produced at moderate cost and which, in practical use, will not be likely to get out of order so as to need attention or repair.

Other and incidental objects will appear 30 hereinafter.

In the drawing:

Figure 1 is a fragmentary side elevation 35 showing a conventional engine of Chevrolet design equipped with our device.

Figure 2 is a transverse sectional view 40 showing the manner in which the device surrounds the branches of the intake manifold of the engine.

Figure 3 is a perspective view showing 45 the heating jacket of the device in detail, and

Figure 4 is a fragmentary section showing 50 the connection between the inlet pipe employed and the exhaust manifold of the engine.

Referring now more particularly to the 55 drawing, we have, for convenience, shown our improved device in connection with a conventional engine 10 of Chevrolet design. However, we do not limit ourselves in this regard since, as will appear as the description proceeds, the heater may be employed in connection with other engines and will prove highly effective wherever found applicable. The intake manifold of the engine is indicated at 11 and the exhaust manifold at 11', the intake manifold being formed with

a vertically disposed trunk from which lead oppositely directed lateral branches connect to the engine head.

In carrying the invention into effect, we 60 employ a cylindrical jacket 12. This jacket is preferably formed of suitable thin resilient sheet metal and is split from end to end thereof. Shaped to close the jacket at its ends are end rings 13 each secured for a portion of its outer circumference to the jacket. Each ring will thus tie a portion of one end of the jacket against circumferential flexing while the remaining portion of said end is free. Like the jacket, the end rings 65 are also preferably constructed of suitable resilient sheet metal and at the lower side of the jacket said rings are split, the split in each ring registering with the split in the jacket and the ring at one side of the split being free of the jacket, as shown clearly in Fig. 3. Formed in the lower side of the jacket at the split therein is a medially disposed circular opening 14 and extending through the bottom of the jacket at said split is an outlet tube 15 located near one end of the jacket and suitably secured to the jacket wall. Entering the jacket at its 70 upper side is an inclined inlet tube 16 which may also be secured to the jacket wall. As 75 will be observed, the jacket is provided with a semi-circular notch 17 in one side of the split adapted to snugly fit about the tube 15 so that the edges of the jacket at the split 80 may be brought together forming a closed joint. The outer ends of the tubes 15 and 16 are split and extending laterally from each of said tubes is a pair of spaced ears 85 18 through which is freely engaged a clamping bolt 19.

To apply the jacket, the front portion 90 thereof is inserted behind the branches of the manifold 11 and then brought forwardly over said branches, and free portions of the end rings 13 being coincidentally engaged 95 around the branches. The opening 14 in the jacket wall is of a size to snugly receive the trunk of the manifold therethrough so that the edges of the jacket may be brought into abutting relation and then joined in any convenient or preferred manner. The 100 free portions of the end rings 13 may then also be connected to the wall of the jacket at its ends for closing the joints between said rings and the jacket and, preferably, tightly closed joints are then formed between the end rings and the branches of 105 110

the manifold as well as between the wall of the jacket and the manifold trunk. As will be seen, the jacket may be readily applied and will provide a closed chamber about the manifold. Soldered or otherwise secured to the exhaust manifold 11' is a nipple 22 at the inner end of which is a spoon 23 and leading from said nipple is a preferably flexible pipe 20 fitting in the inlet tube 16 of the jacket. Leading from the tube 15 is a similar outlet pipe 21, the pipes being secured within said tubes by the clamping bolts 19.

As will now be readily understood in view of the preceding description, when starting the engine, exhaust gases from an initial explosion in any one of the engine cylinders will be diverted through the pipe 20 into the jacket to circulate within the jacket around the intake manifold and finally flow out through the pipe 21, being confined by the jacket about the manifold, so that the portion of the intake manifold enclosed by the heater will, in turn, be heated. Consequently, fuel gases flowing through the manifold will, upon coming in contact with the heated portions of the walls thereof, be considerably raised in temperature while any particles of liquid fuel in the mixture will be vaporized so that the engine may be quickly started. Furthermore, the presence of the jacket upon the manifold will, under

working conditions, serve to maintain the manifold constantly heated to facilitate vaporization of fuel mixture and increase the efficiency of the engine.

Having thus described the invention, what is claimed as new is:

1. An intake manifold heater including a split resilient jacket adapted to be sprung over the manifold, and end members each secured for a portion of the length of the outer edge thereof to the jacket, the end members constituting closures for the jacket. 40

2. An intake manifold heater including a longitudinally split resilient jacket, and radially split end rings each having its split aligned with the split in the jacket and each secured at one side of the split therein for a portion of the length of its outer edge to 50 the jacket, said rings constituting closures for the jacket. 45

3. An intake manifold heater including a split resilient jacket, split end rings forming end closures for the jacket and each 55 attached along a portion of its outer edge to the jacket and having its remaining portion free, and radially disposed inlet and outlet tubes carried by the jacket, the outlet tube being located at the split in the jacket. 60

In testimony whereof we affix our signatures.

WILLIAM A. YOUNG. [L.S.]
GEORGE R. MOORE. [L.S.]
